UNITED STATES PATENT OFFICE.

JOHN W. BUTLER, OF BETHEL, CONNECTICUT, ASSIGNOR, BY DIRECT AND MESNE ASSIGNMENTS, OF ONE-HALF TO FRANK G. METCALF, OF BETHEL, CONNECTICUT.

VAPORIZER

1,314,386.

Specification of Letters Patent. Patented Aug. 26, 1919.

Application filed February 18, 1918. Serial No. 217,784.

To all whom it may concern:

Be it known that I, JOHN W. BUTLER, a citizen of the United States, residing at Bethel, in the county of Fairfield and State 5 of Connecticut, have invented a new and useful Improvement in Vaporizers; and I do hereby declare the following, when taken in connection with the accompanying drawings and the characters of reference marked 10 thereon, to be a full, clear, and exact description of the same, and which said drawings constitute part of this application, and represent, in—

Figure 1 a side view of parts of a motor 15 engine illustrating the location of my improved vaporizer.

Fig. 2 an enlarged vertical sectional view of the vaporizer.

Fig. 3 an end view of the vaporizer, de- 20 tached.

Fig. 4 a transverse vertical sectional view of the same.

This invention relates to an improvement 25 in vaporizers particularly adapted for gasoline engines. In the more general arrangement of engines vaporized gasoline is taken directly from the carbureter to the intake manifold; and while this vapor is more or less in the nature of gas, particles of gaso- 30 lene pass to the manifold, and hence form carbon in the cylinders and the discharge from the exhaust is a noxious gas. Attempts have been made to superheat the vapor as it passes from the carbureter to the intake 35 manifold from the exhaust, but if all the heat from the exhaust is applied for this purpose, the heat is too great and the vapor or gas is liable to explode.

The object of this invention is to provide 40 a vaporizer which will be heated by a portion of the exhaust vapor; and the invention consists in the construction hereinafter de- scribed and particularly recited in the claim.

In carrying out my invention, I employ 45 a heating chamber adapted in size and form for the particular engine with which it is to be used, and adapted to be secured to a carbureter 6 and an intake manifold 7. Mounted in the ends of this chamber, are a 50 series of gas tubes 8 herein shown as seven in number through which vapor passes from the carbureter to the intake manifold. Opening out of the exhaust manifold 9 is a pipe 10 the end of which is connected with 55 a T-fitting 11 mounted on, and opening

into the chamber 5, and in the bottom of the chamber 5 is an auxiliary exhaust pipe 12. It will be noted that the diameter of the pipe 10 is comparatively small as compared with the capacity of the exhaust manifold, so that 60 only a portion of the hot gas from the exhaust manifold passes through the chamber 5, but this is sufficient to superheat and vaporize the mixture passing from the carbureter to the intake manifold. It may also be noted 65 that the cubic capacity of all the tubes 8 is less than the cubic capacity of the intake passage so that the passage is constricted through the vaporizer, and gases or vapors passing through the tubes, are subjected to 70 much higher velocity of travel than the velocity of the intake passage proper. Owing to this increased velocity, together with the smaller volumes of gases or vapors in each tube, the liquid particles are stretched, 75 pulled apart or broken up into smaller liquid particles or vapor, which, when heated, complete the vaporization into a dry uniform mixture. Fuel mixture thus admitted to the intake manifold is vaporized and superheated 80 so that when explosion takes place in the cylinder, the combustion will be so nearly perfect that no unburned gases pass into the exhaust manifold.

Preferably and as herein shown, I mount 85 a tubular arm 13 in the T-fitting 11 and provide the upper end of the arm with a removable plug 14, so that before starting a cold engine hot water may be passed through the chamber 5 by removing the plug 90 14 and pouring water into the arm 13, this water passing through the chamber 5 around the tubes 8 and out of the auxiliary exhaust pipe 12. It will be understood that the heating chamber will be of such dimension 95 as is required by a mathematical calculation governed by variations in piston displacements, and the particular form of the chamber may be varied according to the flanges on the manifold and carbureter with 100 which it is connected. By taking only a portion of the heat from the exhaust manifold, I am enabled to automatically control the temperature in the heating chamber by 105 using a pipe of predetermined capacity, and thus avoid the use of adjusting valves, as too much heat interferes with the proper vaporizing of gasoline, and unless there is sufficient heat the vaporizing will not be 110 properly accomplished.

I claim:

The combination with an explosive engine, of a heating chamber separate from the exhaust manifold and located in the line of the intake passage, and comprising a casing having integral ends, a series of tubes mounted in said ends, said tubes being arranged within the diameter of the intake passage so as to form a constriction of the intake passage through which tubes all of the vapor

in the intake passage flows, and means for conducting a heating medium through the heating chamber.

In testimony whereof, I have signed this specification in the presence of two subscribing witnesses.

JOHN W. BUTLER.
